METHOD OF MAKING PIANO-HAMMERS.

1,374,974.

Specification of Letters Patent.

Patented Apr. 19, 1921.

Application filed August 2, 1920. Serial No. 400,770.

To all whom it may concern:

Be it known that I, IGNATIUS WROZINA, a subject of Austria, and residing at the city of Bridgeport, in the county of Fairfield, 5 and State of Connecticut, U. S. A., have invented certain new and useful Improvements in Methods of Making Piano-Hammers; and I do declare the following to be a full, clear, and exact description of the 10 invention, such as will enable others skilled in the art to which it appertains to make and use the same.

This invention relates to certain new and useful improvements in a method of making 15 piano hammers whereby the felt faces of the hammers may not only be expeditiously and easily toned but also may be thoroughly and properly toned.

Heretofore, it has been the practice to assemble the hammers within a "tray" to receive the felt facing in a continuous strip subsequent to which the felt was cut so as to provide each individual hammer with a felt face. The hammers were then toned twice, 25 first, by the bench toner, who would tone them in the rough by forcing the usual toning needles into the striking face of the felt, and secondly, by an expert after the hammers had been assembled within a piano. 30 This method was very tedious and required considerable skill on the part of the toner who had to exercise the greatest care so as not to fray the edges of the felt. The edges would become ragged and ravelly at the corners if the needles penetrated the felt at the corners, and thus render an imperfect toning and the tone when striking the piano string would not be of the proper timber and mellowness. Moreover, both the bench and expert toning were necessarily only superficial, 35 that is to say, the toning needles penetrated the felt but a short distance, because of the fear that a deep penetration of the felt near the angular edges would break or fray the 40 felt and cause a harsh tone. This would also be the result when the edges of the felt were broken and frayed by striking the same with the toning needles.

It is, therefore, the principal object of this 50 invention to overcome and obviate the above difficulties and imperfections, and the invention consists in the steps and sequence of steps hereinafter described and claimed, reference being had to the accompanying drawing wherein:

Figure 1 shows the several piano hammers clamped within what is termed a "tray," in the piano art:

Fig. 2 is a view disclosing the hammers with the continuous or integral felt facing strip affixed thereto prior to cutting the same up into individual felted hammers, and also showing the active face portion of the continuous felt strip toned by penetrating the same with the usual toning needles: 60 65

Fig. 3 is a vertical section on line 3—3 of Fig. 2:

Fig. 4 is a fragmentary plan view of the felt strip *per se*; and

Fig. 5 is a transverse section on line 5—5 of Fig. 4.

My improved process follows the initial steps of assembling the wooden backs 1 of the hammers within the tray 2, where they are securely and firmly clamped by the bolts 75 3 with the top edges flush, and the integral felt strip 4 is then affixed to the face portions of the assembled hammers. Owing to the fact that the hammers for the lower tones are shorter a filler block or strip 5 is 80 inserted therebeneath in the tray. The invention consists in toning the felt strip while in its continuous or integral state and prior to severing the assembled felted hammers into the individual hammers. To this end 85 the strip is toned by penetrating the striking area throughout its length, as indicated in Fig. 3, subsequent to which the hammers are divided or separated by cutting through the strip at each line of division between 90 the assembled hammers. After being toned the cutting knife is operated between the wooden backs 1 and carried through the felt to separate the individual hammers, when the edges will be found intact with no raggedness or raveling. 95

The felt strip, which is used to face the hammers, is triangular in cross section and tapers lengthwise thereby varying in thickness, the thinner portion facing the hammers used for the higher tones and the thicker portion facing those for the lower tones. In practice this felt strip is placed over a female die with the angular portion of the strip uppermost, and the tray with 100 the assembled hammers is used as the male die, the hammer bodies, extending directly against the angular part of the felt strip. The tray is then subjected to enormous pressure to drive the felt down within the fe- 110

male die so that it will conform closely to the hammers which have been previously covered with glue and thereby face the assembled hammers with a single continuous strip of felt which is now toned before dividing the same.

The individual toning of the hammers is thus obviated and replaced by the far less tedious and more expeditious step of toning 10 the strip while in its entirety.

This improved method eliminates both the bench and expert toning, and also gives a far better toning. Moreover, no subsequent toning is necessary because the toning 15 needles penetrate clear through the felt body, and the toning is effected throughout the entire striking faces of the hammers, which is practically impossible to accomplish under the former practice.

Also, by the old method the felt frequently separated from the sides of the hammer bodies for two reasons,—first, because the felt is bent against its greatest resistance around the hammer bodies and 20 therefore the glue is often insufficient to resist the resilient tendency of the felt, and second, because the penetration of the felt by the toning needles always relieves this 25 resilient tendency, but the needles do not penetrate deep enough to afford complete relief. By the present method the needles 30 penetrate the entire body of the felt and therefore there is effected a complete relaxa-

tion of this resilient tendency and the felt body adheres absolutely to the wooden hammer body.

What is claimed is:

1. The method of making piano hammers, consisting in assembling the hammer bodies within a holder, affixing a continuous strip 40 of felt facing to the hammer bodies, toning the entire striking area of the strip by penetrating the same with toning needles, and then separating the hammer bodies and the strip into individual hammers.

2. The method of making piano hammers, consisting in first applying a continuous strip of felt to the faces of the hammer bodies, and then toning the continuous felt 45 facing strip prior to separating the same into individual striking faces.

3. The method of making piano hammers, consisting in toning the continuous felt facing strip after the same has been affixed to a plurality of assembled hammer bodies and 50 before the whole has been separated into individual hammers.

4. The method of making piano hammers, consisting in first applying a continuous strip of felt to the faces of the hammer 55 bodies, then penetrating the striking area of the strip of felt facing to the full depth, and finally separating the same into individual striking faces.

In testimony whereof I affix my signature. 65
IGNATIUS WROZINA.
